UNITED STATES PATENT OFFICE.

WILLIAM HENRY BOOTH, OF BATON ROUGE, LOUISIANA.

MAGAZINE TACK HAMMER.

Application filed April 12, 1924. Serial No. 706,068.

To all whom it may concern:

Be it known that I, WILLIAM H. BOOTH, a citizen of the United States, residing at Baton Rouge, in the parish of East Baton Rouge and State of Louisiana, have invented certain new and useful Improvements in a Magazine Tack Hammer, of which the following is a specification.

This invention relates to improvements in magazine hammers.

The primary object of the invention is the provision of a magazine hammer embodying novel means for feeding tacks from a supply container within the hammer to a driving head, in a positive and efficient manner, so that the hammer may be used in any position, nothing being dependent upon force of gravity to prevent use of the hammer in various positions.

A further object of this invention is the provision of novel dispensing means for feeding of tacks from a supply source to the driving head of a hammer.

Other objects and advantages of this invention will be apparent during the course of the following detailed description.

In the accompanying drawings, forming a part of this specification, and wherein similar reference characters designate corresponding parts throughout the several views,

Figure 1 is a side elevation, partly in section, of the improved magazine tack hammer.

Fig. 2 is a fragmentary cross sectional view taken through the driving head construction of the tack hammer, showing more particularly the association of novel carriage and dispensing mechanism therewith.

Fig. 3 is a cross sectional view taken through the improved tack hammer driver head construction, showing the position of parts of the hammer as the tack is being driven.

Fig. 4 is a cross sectional view taken substantially on the line 4-4 of Figure 3.

Fig. 5 is a side elevation of a novel carriage member which is used for receiving a tack and placing it upon a driving head.

Fig. 6 is a cross sectional view taken through the improved tack hammer substantially on the line 6-6 of Figure 2.

Fig. 7 is a cross sectional view taken through the tack hammer substantially on the line 7-7 of Figure 2.

Fig. 8 is a fragmentary cross sectional view taken substantially on the line 8-8 of Figure 7, and showing more particularly novel dispensing features of the tack hammer, and

Fig. 9 is a cross sectional view taken through the handle of the tack hammer, showing a novel channel or track way therein for the conveying of the tacks from a supply source to a dispensing mechanism, this view being taken substantially on the line 9-9 of Figure 1.

In the drawings, wherein for the purpose of illustration is shown only the preferred embodiment of the improved magazine tack hammer, the letter A may generally designate this hammer, which may consist of a handle structure B; driving head construction C; track way D; dispensing means E; and a carriage F for conveying tacks from the dispensing means E to the driving point on the head construction C.

The handle B is preferably hollow, providing the compartment 10 therein along which the track way D extends. In the handle grasping portion of the handle B, a tack container 11 may be positioned, which opens through the rear end of the handle B, and is normally closed by a cap 12 which may be removed for the purpose of placing a supply of tacks in the container 11.

The track D is preferably of channel shaped formation, providing a slot or way 13 extending longitudinally thereof, which is to receive the head portions of the tacks, and the track D is provided with a slot 14 in the bottom thereof through which the shanks of the tacks depend as the tacks are moved along the track way D toward the dispensing mechanism E.

The driver head construction C of the hammer preferably includes a substantially cylindrical shaped casing 16, which is formed rigid at the forward end of the handle B. This casing 16 provides a compartment 17 therein which receives the main portion 18 of the driver head construction. This portion 18 is of bifurcated substantially cylindrical shaped formation, and at its upper end this member 18 is formed integral with a detachable cap 19 which may be screw threaded in the upper end of the casing 16, so that it may be readily removed from the compartment of the casing 16. The main body portion 18 is, in fact, a

magnet, and the spaced legs 25 and 26¹ provide opposite poles of the magnet, the space 30 between the legs or poles 25 and 26¹ being a slot which extends upwardly along the driver head portion 18, to a point above the dispensing mechanism E, for a purpose which will be subsequently described. The slot 30 narrows at the free end of the driver head legs 25 and 26¹, and provides shoulders 26 facing upwardly in the slot, which are adapted to cooperate in tripping a tack placing finger 32, as will be subsequently described. The lower surface 33 of the driver head part 18 is adapted to receive the head 15 of the tack thereon, so that it may be held in position by magnetism, to permit the driving of the tack.

Referring to the dispensing mechanism E which is adapted to place the tack upon the carriage F so that it can be conveyed to the surface 33 of the driver head part 18, the same includes a slide casing 40, which is slidably disposed on the track way D, and receives the latter in a suitable opening provided longitudinally therethrough. The track way D, at its forward end, is slotted on the upper wall thereof, as at 41, and a spring 42 is fixedly carried by the upper wall of the track way D, at the extreme forward 30 end of the track way, the spring having the free end thereof depending into the area along which the heads of the tacks travel, so as to retard travel of the tacks. The sliding part 40 of the dispensing mechanism E pivotally 35 carries a pawl or dispensing arm 43, which is urged by spring 44, so that the free end 45 of the same extends beneath the track way D, immediately below the slot in the track way, so that the free end of this arm 43 40 may engage the shank of the foremost tack, and push the tack forward in the track way D, as the slide part 40 is moved forward, for the purpose of moving the foremost tack past the retarding spring 42, and 45 onto the carriage mechanism F, when the latter is positioned as is illustrated in Figure 3 of the drawings. The rear surface 48 at the free end of the dispensing arm 43 is rounded, so that the arm may readily flex 50 or move past the shank of the foremost tack, as the slide 40 is moved to the rear along the handle, after a dispensing operation has been effected. A spiral spring 49 is preferably carried by the fixed casing portion 50, 55 one end of the spring 49 being held by a stationary pin 51, and the opposite end of the spring being engaged by a lug 52 formed on the sliding part 40 of the dispensing mechanism; the function of the spring 49 60 being to push the slide 40 rearwardly after a dispensing operation has taken place, to position the arm 43 rearwardly of the shank of a foremost tack, so that the dispensing mechanism is in position for another operation. The casing portion 50 is welded or

otherwise secured to the handle. The slide supporting casing 50, at its forward end has a pair of upstanding arms 56 and 57, which pivotally receive a bell crank 58 at their upper ends. One end 59 of the bell crank 70 extends downwardly for connection to a pair of upstanding attaching arms 60 and 61 of the slide 40; a pin being carried by these arms 60 and 61, which extends through a slot 63 provided in the bell crank end 59. The other end portion 65 of the bell crank 75 extends for operation by a pivoted lug or finger 68 of the carriage mechanism F, as will be subsequently described.

Referring to the carriage mechanism F, 80 the same is mounted for travel longitudinally of the driving head construction C, and consists mainly of the tubular portion 70, having the passageway 71 therein for slidably receiving the main part 18 of the driving head. The tubular portion 70 is slidably disposed through an opening 72 in the lower wall of the driving head casing 16 so that the same may extend outwardly of the driving head construction C. Inwardly of the compartment 17, the tubular portion 70 of the carriage is provided with a flange 75, and a spiral actuating spring 77 is placed about the main part 18 of the driving head, and at one end engages the cap 19, and at its other end engages the inner end of the tubular portion 70 of the carriage F, to force said tubular portion outwardly from the driving head, in the position illustrated in Figure 2 of the drawings. The tubular portion 70, at its upper end, and within the driver head casing 16, supports the spaced arms 80 and 81, providing a slot 82 therebetween. In this slot 82, the trip member 32 is pivoted, as by a pin 84, and this trip member 32 has a lug end 85 which normally extends into the slot 30 between the spaced leg portions 25 and 26 of the driver head part 18. The trip member of trip arm also has a spring 88 which normally acts to push the lug 85 into the slotted way 30, and to move the free end of the trip member 32 against the head of a tack after the same is received in the transverse way 90 of the carriage mechanism. The lug or finger 68 pivotally carried by the carriage mechanism F, within the compartment of the driver head casing 16, is placed upwardly of the trip member 32, and supported in the slot 82 by a pin 92. This finger 68 may move upward from its pivot pin 92, but a pin 93 is placed so that the finger 68 cannot move downwardly, and a spring 94 normally urges the finger 68 against the stop pin 93, so that it is in position for operating the dispensing mechanism, as will be subsequently described.

In operation, the tacks will be fed along the channel shaped track way D, incident to natural movement of the hammer during 130

a tack driving operation. The tacks will move along this track way D, and at the forward end of the track way D the tacks are retarded in their further movement by 5 means of the retarding spring 42. The blow for the driving operation sends the carriage F upwardly in the casing 16, along the driver head part 18, so that the tack which is supported upon the lower end of 10 the magnet is driven; the carriage being adapted to move entirely upwardly in the casing 16, into the position illustrated in Figure 3 of the drawings, to expose the tack so that it may be driven. This upward movement of the carriage F in the driver head causes the laterally extending finger or lug 68 to engage the portion 65 of the bell crank lever 58, and will rock the bell crank lever 58 into the position illustrated 15 in Figure 3. This will cause the sliding part 40 of the dispensing mechanism E to move forwardly along the track way D, and the free end 45 of the dispensing arm 43, engaging rearwardly of the shank of the foremost tack, will shove this foremost tack forwardly past the retarding spring 42, and the head of this tack will enter the transverse passage 90 in the carriage F. When 20 the blow has been completed and as the driver head is being lifted, the spring 77 will assert itself and force the carriage F outwardly from the driving head. This will cause the finger 68 to move out of operating relation with the bell crank 58 of 25 the dispensing mechanism E, and the spring 49 of the dispensing mechanism E will operate to cause the slide 40 to move rearwardly along the trackway, so that the dispensing arm 43 will be positioned rearwardly of the shank of the foremost tack, in the position 30 illustrated in Figures 2 and 8 of the drawings. It is to be noted, that when the carriage F moves to its uppermost position within the casing 16, the lug 85 of the trip member 32 engages the upper end of the slot 30, and causes this trip member 32 to move out of obstructing relation with the transverse passageway 90, so that the dispensing mechanism can properly insert the 35 foremost tack into carrying relation on the carriage F. However, upon the downward movement of the carriage mechanism, the spring 88 will cause the trip member 32 to move into engaging relation with the head 40 of the tack which is carried by the carriage F, and when the carriage mechanism F has reached its outermost position with respect to the driving head C, the tack head will not rest against the main part 18 of the 45 driving head structure, so that the spring operated trip 32 will force the tack onto the supporting surface 33 of the magnet, and will thus position the tack as illustrated in Figure 2 of the drawings, so that it is ready 50 to be driven.

From the foregoing description of this invention it is apparent that a novel principle of operation for magazine hammers has been provided, which will insure the progressive dispensing of tacks upon the 70 driving head of a hammer, notwithstanding the location of the hammer, nor the environment in which it may be used.

Various changes in the shape, size, and arrangement of parts may be made to the 75 form of the invention herein shown and described, without departing from the spirit of this invention or the scope of the claims.

I claim:

1. In a magazine tack hammer the combination of a driving head construction, means for receiving a supply of tacks, a carriage, means for dispensing the tacks onto the carriage, and means for placing the tacks from the carriage onto the driving 80 head.

2. In a magazine hammer a driving head structure, means for receiving a supply of tacks, and carriage means movable along the driving head construction so that it may be 90 positioned to receive a tack and place it on said driving head construction.

3. In a magazine tack hammer the combination of a driving head, a track way for supply of tacks, and means slidably carried 95 by the driving head and moving longitudinally thereof for individually dispensing the tacks from the track way to said driving head.

4. In a magazine tack hammer the combination of a driving head, a carriage movable with respect to the driving head, means for feeding tacks to the carriage, and means for feeding tacks from the carriage to the 100 driving head.

5. In a magazine tack hammer the combination of a hammer including a driving head and a handle, container means in the handle for receiving a supply of tacks, a carriage supported by the driving head, and a dispensing mechanism operable by said carriage mechanism to dispense a tack onto the carriage.

6. In a tack hammer of the class described, the combination of a driving head, container means for a supply of tacks, dispensing means for dispensing the tacks, a carriage for operating said dispensing means for the dispensing of tacks individually to the carriage, and means for moving a tack from the carriage onto the driving head.

7. In a magazine tack hammer the combination of a driving head including a magnet, a handle structure, tack supply means in the handle structure, means carried by said handle structure for dispensing a tack from the tack supply means, and means slidably carried by the driving head and movable longitudinally thereof upon the 125 130

magnet for receiving the tack after it has been dispensed for placing it on the lower end of said magnet.

8. In a magazine tack hammer the combination of a dispensing mechanism including a tack supporting track way, a member 10 slideable longitudinally on the tack supporting track way, a dispensing arm pivotally carried by said sliding member for dispensing tacks forwardly along the track way, and a retarding spring carried by the track way for normally retarding passage of tacks therealong.

9. In a dispensing mechanism for tack 15 hammers the combination with a track way, of a retarding spring for normally retarding passage of tacks along said track way, sliding means on the track way including a pivotally mounted arm normally urged to 20 extend behind a tack for urging it along the track way past said retarding spring as the same is slid therealong, and spring means normally urging the sliding means to 25 position the free end of its pivoted arm rearwardly of a tack on said track way.

10. In a dispensing mechanism for tack hammers the combination of a supporting casing, a tack receiving track way, a sliding member in the casing receiving the track 30 way therein, a bell crank lever pivoted on said casing and engaging the sliding member for movement of the latter upon its pivotal movement, an arm carried by said 35 sliding member for engaging tacks on said track way, and spring means normally urging the sliding member to position its arm rearwardly of a tack.

11. In a tack hammer construction of the character described the combination of a 40 driver head structure including a bifurcated magnet, a carriage slideable along the magnet including a space for receiving a tack therein, a trip member pivotally supported

by the carriage including a head extending into the space between the bifurcations of the magnet, said bifurcations of the magnet being formed to engage the trip member when the plunger is in a predetermined position with respect to the driver head to move a tack supported by the carriage onto the magnet for support thereby.

12. In a magazine tack hammer the combination of a driving head construction, a handle for the driving head construction, tack supply means for the handle, a dispensing mechanism including an operating lever, a carriage operating along the driving head construction including a finger for operating the lever of said dispensing mechanism for dispensing a tack onto said carriage, and means operated by the driving head construction and by said carriage for moving a tack from the carriage onto the driving head construction when the carriage has moved into a predetermined relation with respect to the driving head construction.

13. In a magazine tack hammer the combination of a driving head, a handle, means for dispensing tacks from the handle, a carriage movable along the driving head construction, means normally urging the carriage outwardly of the driving head construction, a trip member pivoted on the carriage, an arm pivoted on the carriage adapted for operating said dispensing mechanism 70 to move a tack from the latter onto said carriage when the carriage is inwardly of the driving head construction, and means for operating the trip mechanism when the carriage is most outwardly positioned with 75 respect to the driving head construction for forcing a tack which is carried thereby onto the driving head construction in a driving relation therewith.

WILLIAM HENRY BOOTH.
